CAPSTAN

Filed March 28, 1928

Inventor
HERMAN S. ALBRECHT

By: *Ben V. Gillman*
Attorney

UNITED STATES PATENT OFFICE

HERMAN S. ALBRECHT, OF ST. LOUIS, MISSOURI

CAPSTAN

Application filed March 28, 1928. Serial No. 265,348.

My invention relates to improvements in capstans, and more particularly to those capstans having a shaft centrally therethrough, and has for its principal objects the production of such a capstan which shall be simple, convenient, extremely sturdy and long-wearing in construction, reliable, and efficient and satisfactory for use wherever found applicable.

10 With the capstans now in use, especially those having a central shaft therethrough and using a speed-reducing gearing between the drive and driven members, there is a very great strain imposed on the shaft whenever 15 the load is on, such a strain tending to bend the shaft and perhaps break it, and acting to throw the parts of the mechanism out of true alignment.

One of the objects of my invention is to 20 construct such a capstan, but wherein the transverse, lateral or side strain is taken off the shaft and transmitted to the base member, said base member being of comparatively larger size than the shaft and better able 25 to withstand such strains.

Another object of my invention is to provide means of the kind described, wherein the winding barrel of the capstan will not rest directly upon the base member, as with usual 30 construction, to cause undue wear therebetween, but, on the contrary, will be spaced therefrom and maintained in said spaced relationship by means of anti-friction elements, and whereby the side thrust is transmitted 35 from said barrel to said base member.

Another object of my invention is to so construct the co-operating parts of the base and barrel of the capstan, that said anti-friction members may be inserted into place 40 without in any way dismantling or taking off any of the members, said anti-friction members being put into position after the finished assembling of the capstan, from without the parts thereof, and said means may be 45 adjusted to compensate for wear or for better centering, etc., from the exterior of the capstan.

Many other objects and advantages of the construction herein shown and described will 50 be obvious to those skilled in the art to which

this invention appertains, from the disclosures herein given.

To this end my invention consists in the novel construction, arrangement, and combination of parts herein shown and described, 55 and more particularly pointed out in the claims.

In the drawing, wherein like reference characters indicate like or corresponding parts throughout,

The figure is a vertical cross-sectional view, some of the parts being indicated in plan view for the sake of clearness.

In said drawing, wherein I have illustrated a preferred embodiment of my invention, there is shown a capstan, particularly intended for marine service, and comprising the three main members, the head, barrel and base members, respectively, and numbered as 1, 2 and 3, respectively. The driving power is applied at the head member to rotate the same, the pockets 4 being shown for receiving bars for this purpose. The rotation of the head member is thence imparted to the barrel member with a reduced speed, by means of suitable mechanism such as gearing or the like, as shown, said barrel being elongated and adapted to have a length of cable or the like flexed or wound thereabout, in the usual manner.

A shaft 5 extends upwardly from the base member 3 and passes through both the barrel and head members. Said barrel member is hollow and is provided with a depending annular flange 6 about the bottom thereof, for a purpose to be more clearly hereinafter described.

The head member is rotatably supported on the top face of the barrel member and is provided with an elongated, hollow sleeve 7 which extends downwardly through the barrel member and terminates adjacent the lower end of the latter, and receiving the shaft 5, said shaft projecting above the top of said head, if desired. Ratchet teeth 8 are provided in the top face of the barrel in an annular series, and vertically slidably pins, tapered at the bottom, are provided in openings through the head and are engageable with the ratchet teeth 8, said pins being indicated at 9.

This permits the head to be rotated relatively to the barrel, in one direction, the pins ratcheting over said teeth, but preventing relative rotation in the opposite direction. A dome or cover 10 is preferably placed over said head member, as shown.

In a chamber formed between the lower end of the barrel member and the upper end of the base member, there is arranged the speed-reducing gearing. A gear plate 11 is rotatably mounted on the shaft, said plate carrying a plurality of pinion gears 12 thereon, said gears being rotatably mounted on stub shafts 13 spaced circumferentially around the gear plate. A center gear 14 is rotatably mounted on the shaft, above the plate, and meshes with all of said pinion gears. The inner wall surface of said barrel 2 is provided with an annular series of gear teeth 15, adapted to mesh with and be engaged by the teeth of the pinion gears.

The center gear 14 is keyed to the head member 1, in any suitable manner, as by forming mating lugs and pockets in the lower end of the sleeve portion of the head member and the top of the center gear, as indicated.

Pins 16 are inserted through openings in the gear plate, so as to be vertically slidable, these pins being tapered at their lower ends 30 and engageable with ratchet teeth 17 provided in an annular series on the top face of the base member. In this manner, rotative movement of the gear plate in one direction is permitted relatively to the base, but is prevented in the opposite direction.

The base member 3 is provided with a pair of upwardly directed annular flanges 18 and 19, there being teeth 20 between said flanges, said teeth being engageable with pawls 21 which are hinged upon and depend from the outer surface of the annular flange 6 of the barrel member.

When it is desired to exert a pull on a cable, the latter (not shown) is looped about the barrel of the capstan and force applied at the head member by rotating it in the proper direction. This rotation is transmitted, by means of the inter-keyed sleeve and gearing, to the barrel member, to cause the latter to rotate more slowly than the head, and in the opposite direction than the latter. The pins 9 and 16, as well as the pawls 21, will slip or ratchet over their toothed run-ways, but will prevent accidental slippage and rotation of the barrel in the opposite direction.

In order to prevent undue strain on the shaft 5 and avoid bending or perhaps breaking the same, I have provided means to cause the base member to take up the transverse or lateral strain imparted to the shaft and barrel.

The co-operating flanges 6 and 19 are constructed so that one encircles the other and they are maintained spaced apart a slight distance. In the embodiment illustrated, the

flange 19 is the inner one and is provided with a substantially semi-circular cross-section groove 22, extending annularly about the outer peripheral surface thereof, forming a race-way. Openings 23 are provided radially through the overhanging flange 6, and are preferably threaded to receive a screw 24, said openings being of sufficiently large diameter to permit of an anti-friction element 25 being inserted therethrough from the exterior side of the flange. These screws 24 are provided with a substantially semi-spherical cavity or pocket at their inner ends for receiving and retaining the anti-friction element in place. Obviously these screws may be adjusted from time to time, as desired, to take up for wear of the race-way, or for any other reason, this adjusting being accomplished from without the capstan, and without dismantling of any of the parts or causing interruption in case the capstan is under operation.

It is to be noted that the barrel member does not rest upon the base member directly, as is usually the case, but is spaced a slight distance thereabove. With such a construction, there is no undue wear between the barrel and base, but the anti-friction elements not only reduce this wear, but they carry the load as well. When the barrel is under load, as in pulling on a cable, the customary transverse or side strains thereon will be transmitted through said anti-friction elements to the base, whereby they will be evenly and uniformly absorbed; and without the danger of any breakage or bending of the shaft. Further, the capstan will run smoother, with less power, and with greater life to its parts.

Having thus described my invention, it is obvious that various immaterial modifications may be made in the same without departing from the spirit of my invention; hence I do not wish to be understood as limiting myself to the exact construction, form, arrangement, and combination of parts herein shown and described, or uses mentioned, except as limited by the claims.

What I claim as new and desire to secure by Letters Patent is:

1. In a capstan mechanism, a head and base member, a barrel member independent of said head member and about which a flexible cable is adapted to be wound, a shaft extending between said base and head members, and means between said barrel and base members to transmit transverse thrust from the former to the latter and limiting relative movement therebetween longitudinally in opposite directions.

2. In a capstan, a head, a barrel, a base, a stationary shaft extending from said base to said head, drive means between said head and barrel for transmitting rotary movement therebetween, and means between said

barrel and base members for transmitting strain between the former and the latter.

3. In a device of the kind described and in combination, a barrel member about which a cable may be wound, a head member drivingly connected to said barrel member, a base member independent of said head member and spaced from said barrel member and having an annular race-way therein, and a plurality of anti-friction elements carried by said barrel member and engageable in said race-way, whereby said barrel member is supported thereby and the side thrust on said member is transmitted to said base member.

15 4. In a capstan, a rotary head member, a fixed base member having an annular flange provided with a groove peripherally therein, a rotary barrel member between said base and head members and having an annular flange adjacent said first-mentioned flange, a shaft extending between said base and head, means on said shaft for transmitting drive between said head and barrel members, anti-friction means between said pair of flanges 25 and traveling in said annular groove, the outermost of said pair of flanges having a radial aperture therethrough, whereby said anti-friction means are insertable into position after assembly of said capstan.

30 5. In a device of the kind described, and in combination, a capstan head, a base member provided with a peripherally grooved annular flange, a barrel interposed between said members and having a radial aperture therethrough leading inwardly from the peripheral outer surface, a shaft between said base and head members, said base and barrel members being spaced apart, anti-friction elements insertable through said radial aperture through the barrel member from the exterior of the barrel member after assembly of said device, whereby the lateral thrust on said barrel will be transmitted to said base member, and means for retaining said anti-friction elements in their desired positions and adjusting them while in service to compensate for wear of said groove.

6. In a capstan, a head member, a base member, a hollow barrel therebetween and spaced above the latter, a shaft extending from the base to said head member, gearing on said shaft for transmitting rotative movement between said head and barrel members, said base and barrel members having cooperating radially spaced flanges, one encircling the other, an annular race-way on one of said flanges, ball-retaining means on the other of said flanges, and balls in said ball-retaining means and projecting into said race-way, whereby said barrel is supported and lateral thrust on said barrel is transmitted to said base member.

HERMAN S. ALBRECHT.
